United States Patent Office

Des. 215,055
Patented Aug. 26, 1969

215,055

ELECTRONIC GAUGE

James R. Schiller, Grosse Point Woods, Mich., assignor
to Speedring Corporation, Warren, Mich., a corpora-
tion of Michigan

Filed Apr. 5, 1968, Ser. No. 11,315

Term of patent 14 years

Int. Cl. D10—11

U.S. Cl. D26—1

Fig. 1

Fig. 2

Fig. 3

FIGURE 1 is a front view of an electronic gauge illustrating my new design;

FIGURE 2 is a side view of the right side of the electronic gauge; and

FIGURE 3 is a perspective view of the electronic gauge.

The rear of the electronic gauge is substantially flat and plain in appearance and the left side is substantially the same in appearance as the right side.

I claim:

The ornamental design for an electronic gauge, sub-
stantially as shown and described.
